(57) **CLAIM**

The ornamental design for the cabinet for displaying goods, as shown and described.

DESCRIPTION

FIG. 1 is a front, top and right side perspective view of a cabinet for displaying goods showing my new design;

FIG. 2 is a front elevational view thereof;

FIG. 3 is a rear elevational view thereof;

FIG. 4 is a top plan view thereof;

FIG. 5 is a bottom plan view thereof;

FIG. 6 is a right side elevational view thereof; and,

FIG. 7 is a left side elevational view thereof.

The broken lines shown in FIGS. 1, 2, 3, 6, and 7 are for illustrative purposes only and form no part of the claimed design.
